UNITED STATES PATENT OFFICE.

HERBERT ABRAHAM, OF NEW YORK, N. Y., ASSIGNOR TO THE RUBEROID COMPANY,
A CORPORATION OF NEW JERSEY.

INTERLOCKING STRIP SHINGLES.

Application filed May 26, 1922. Serial No. 563,777.

To all whom it may concern:

Be it known that I, HERBERT ABRAHAM, a citizen of the United States, residing in the city, county, and State of New York, 5 have invented a certain new and useful Improvement in Interlocking Strip Shingles, of which the following is a specification.

This invention relates to improvements in prepared roofing strips having their lower 10 edges broken at regular intervals by recesses leading into slots to form shingle-like portions that simulate separated individual shingles when the strips are laid in overlapping courses.

15 One of the objects of the invention is to provide interlocking strips formed with tongues that extend downward of the shingle-like portions and lock into the slots of an underlying strip.

20 Another object is to provide interlocking strips of such shape that they can be cut from a web of prepared roofing material with minimum waste.

A further object is to provide strips that 25 when laid in interlocked relation form an ornamental roof having three thicknesses of material adjacent the slots and thereby giving the roof a desirable massive appearance.

In the accompanying drawings, illustrating 30 a preferred embodiment of the invention,

Figure 1 is a plan view of several of the strips laid in interlocked relation,

Figure 2 is a plan view of one of the 35 strips, and

Figure 3 is a plan view of a length of roofing material indicating the manner of cutting the strips.

The strip comprises an elongated body 1 having its lower edge broken by a recess or re-entering angle 2 which terminates in a parallel-sided slot 3 and divides said edge into two similar shingle-like portions 4. The strip has a shoulder 5 at either end 40 each of which corresponds to half the width of a slot 3. The length of each shingle-like portion 4 is substantially thrice that of a slot 3, both being measured transversely of the strip. Extending across the 45 lower third part of each shingle-like portion 4 is a pair of separated slits 6 the adjacent ends of which are spaced apart a distance substantially equal to the width of a slot 3, said slits forming an integral 50 tongue 7 at the lower end of each of the

portions 4. Preferably the ends of the slits are turned at right angles to their length, as seen in the drawings, to provide a flexible connection for the tongue so that it may be bent without breaking.

60 The strips may be formed from a web 8 with an economical use of material by cutting so that the shingle-like portions 4 of opposite strips interfit as indicated in Fig. 3. In this manner a plurality of strips may 65 be produced without waste other than that caused by cutting out the slots 3.

The strips are laid upon a roof in overlapping courses with the tongues 7 of each course inserted under the slots 3 of the next 70 lower course, as seen in Fig. 1, and they are fastened as usual by nails driven through the body portions above the inner ends of the slots, the nail-heads being covered by 75 the shingle-like portions of the next upper course. When thus laid the several courses are interlocked with the shingle-like portions held down by reason of the engagement of the tongues in the slots, a part of 80 each tongue being visible through the slots, and with substantially two-thirds of the extent of each of said shingle portions exposed to the weather.

85 A roof laid with my improved strips has an attractive and ornamental appearance similar to that of a roof laid with strips of my reissue Patent No. 15,280 of February 7, 1922, but with an additional massive appearance due to the three thicknesses of material 90 adjacent each of the slots.

95 While I have described the invention with particular reference to a "twin shingle," it may be embodied in an individual shingle or in a strip composed of any desired number of connected shingle-like portions. Furthermore, it is to be understood that various modifications in the shape of the strip may be made without departing 100 from the scope of the invention.

105 What I claim is:

1. A roofing strip of flexible waterproof material having along one edge a plurality of projections with intervening spaces, each projection having parallel sides, an angular end, and aligned slits extending inwards from the converging edges of the end, the slits being separated a distance equal to the space between the parallel sides of adjacent projections.

110 2. A roofing strip of flexible waterproof

- material having along one edge a plurality of projections with intervening spaces, each projection having parallel sides, an angular end, and aligned slits extending inwards from the converging end-edges, each strip being laid with the end portion of each projection, below the slits, inserted in the space between adjacent projections of the next lower strip and partly underlying said lower projections, whereby to interlock the strips in overlapped relation.
- 5 from the converging end-edges transversely of the lower third portion of the projection, the slits being separated a distance equal to the space between the parallel sides of adjacent projections.
- 10 3. A roof composed of overlapping strips of flexible waterproof material laid in courses, each strip having along one edge
- a plurality of projections with intervening spaces, each projection having parallel sides, an angular end, and aligned slits extending inwards from the converging end-edges, each strip being laid with the end portion of each projection, below the slits, inserted in the space between adjacent projections of the next lower strip and partly underlying said lower projections, whereby to interlock the strips in overlapped relation.
